I. S. BLEENDES

GUIDE FOR YARN

Filed March 5, 1925

INVENTOR
Isidor S. Blewdes

BY
Charles G. Hensley
ATTORNEY

UNITED STATES PATENT OFFICE.

ISIDOR S. BLEENDES, OF BROOKLYN, NEW YORK.

GUIDE FOR YARN.

Application filed March 5, 1925. Serial No. 13,301.

To all whom it may concern:

Be it known that I, ISIDOR S. BLEENDES, a citizen of the United States, and a resident of the borough of Brooklyn, in the county 5 of Kings, city and State of New York, have invented certain new and useful Improvements in Guides for Yarn, of which the following is a specification.

My invention is adapted more especially 10 for use in cone winding machines although it will be apparent that the same may be used on other types of machines in which yarn or similar material is unwound from a skein. In the drawing I have shown my 15 invention applied to a cone winding machine, only such parts of the machine being shown as is necessary to illustrate the application of my invention. In cone winding machines it is customary to place the 20 individual skeins of yarn upon a pair of reels and a series of reels are generally arranged in double rows at the front and back of the machine. The yarn is taken from each skein and is wound into the form 25 of a cone or bobbin and as the yarn is drawn from the skein the latter moves around like a belt upon its reels. The skeins cannot be placed under great tension between the reels as there would be too much resistance or 30 tension upon the yarn, which would cause the latter to break, so a light tension is usually furnished by making the lower reel of the pair swing by gravity on a pivoted arm. Owing to the light tension on the 35 skein of yarn, one or more of the strands often jumps over the flanges of the reels and the strands of adjacent skeins often entangle with each other interfering with the operation of the winding machine. The ob- 40 ject of my present invention is to provide a simple and inexpensive guide for straddling the upper and lower runs of each skein of yarn to prevent the yarn from jumping over the flanges of the reel and 45 also to prevent the yarn of adjacent skeins from becoming entangled. It is not practicable to enlarge the flanges of the reel beyond certain reasonable limits as this in- 50 creases the weight of the reels and thereby increases the tension of the yarn beyond practical limits. The present device, while serving to guide the skein and avoid the difficulties mentioned above, nevertheless does not increase the tension upon the yarn.

In the drawing forming part of this application, 55

Figure 1 is a side elevation showing the parts of a cone winding machine with which my present invention is associated,

Figure 2 is a sectional view thereof taken 60 on the line 2—2 of Figure 1,

Figure 3 is an end view of the parts shown in Figure 1, and

Figure 4 is a perspective view of the guide detached from the machine. 65

In the drawing I have shown the central shaft 1 on which are mounted brackets 2 for supporting the diverging arms 3, 4 which form the supports for the inclined skeins of yarn, the arms 3 being directed obliquely 70 toward the front of the machine and the arms 4 being directed obliquely toward the rear of the machine, in the usual manner. These arms are pivoted to the bracket 2 on the pivots 5 the inclination of the arms being adjustable by means of pins inserted in the apertures 6 of the bracket. As the several arms in the machine are duplicates of each other a description of one will suffice for all. Usually each arm 4 supports a 80 pair of reels at each side of the arm, each pair of reels serving to hold a skein of yarn. In the drawing I have shown an upper reel 7 and a lower reel 8 in line with each other to support and guide a skein of 85 yarn 9. At the opposite side of the arm 4 there is a similar pair of reels 7 and 8 serving to support another skein of yarn 10. There is a clamp 11 which is adjustable along the arm 4 and it carries the angular 90 bracket 12 which projects away from the arm 4 and on its outer end it supports a shaft 13 on which both reels 7 are adapted to freely revolve. By adjusting the clamp 11 along the arm 4 the reels 7 may be sepa- 95 rated from the reels 8 the required distance to hold any size skein upon the reels. In the form shown herein each reel comprises a hub 14 on which are mounted parallel flanges 15 which are connected by cross 100 spokes 16 with which latter the skein engages.

The lower reel 8 of each pair is mounted to revolve freely upon the shaft 17 which is carried on the free end of a bracket 18 which is pivoted at 19 to the arm 4. The reels 8 tend to swing from the pin 19 as the center and this gravitational action places the skein

which is supported upon the reels 7 and 8 under light tension. A strand of yarn 20 usually is taken from the skein near the upper reel, 7. The improved guide shown here-
⁶ in is preferably mounted by means of a bracket 21 and a clamp 22 upon the arm 4 and the position of the bracket may be ad-
¹⁰ justed along the arm 4 by means of the set screw 23. In the free end of the bracket 21 there is journaled a short shaft 24 the posi-
¹⁵ tion of which may be adjusted and fixed by means of a set screw 25. A pair of guides may be supported upon this shaft 24 for the skeins at opposite sides of the arm 4 and as these guides are duplicates of each other a description of one will apply to both. This guide is preferably made of wire or rod bent into the form of a series of loops in the manner described below. The upper horizontal
²⁰ end 26 of the guide extends through an aperture in the shaft 24. From the portion 26 the wire is bent downwardly at 27 thence looped at 28 to form a return portion 29 ex-
²⁵ tending parallel to the portion 27. At the upper part of the portion 29 the rod is bent at an angle to form a cross piece or connec-
³⁰ tion 30 extending substantially at right angles to the portions 27 and 29, and the rod is again bent downwardly to form a portion 31 parallel to and spaced from the portions 27 and 29. At 32 the rod is again bent into a loop and it then extends upwardly to form a part 33 which is parallel to the parts 27, 29 and 31. The loops 28 and 32 are preferably
³⁵ turned outwardly in divergent relation as shown in Figure 3 to facilitate the placing of the guide over the skein.

When skein of yarn is being applied to the reels 7, 8 the guide as a whole, together with
⁴⁰ the shaft 24, may be swung so that the guide is out of the way while the skein is being mounted, or, the skein may be inserted be-
⁴⁵ tween the sides of the guide from below. In either case the skein may be attached as quickly as if the guide were not present. When the skein is in place on the reels 7, 8 the guide will straddle both the upper and lower runs, the portions 27 and 29 of the guide extending downwardly on one side of
⁵⁰ the skein, and the portions 31, 33 extending downwardly at the opposite side of the skein, the cross member 30 lying above the upper run of the skein. As the space between the sections 27 and 29 and the sections 31, 33 is approximately the same as the distance be-
⁵⁵ tween the flanges 15 of the reels there will be approximately no friction between the guide and the yarn. If there is a tendency for the yarn to jump the flanges of the reels or for
⁶⁰ the yarn of adjacent reels to flop sidewise, this will be opposed by the guide. It is preferable to make the guide extend below the lower run of the skein as shown in the drawing in order to protect any dropping strands of the yarn. The guide may be ad-

justed in its position along the arm 4 and its angular relation to this arm may be adjusted by means of the set screw 25 which controls the rocking of the shaft 24. By this simple and double adjustment the guide may be ar-
⁷⁵ ranged to control the yarn at the critical point regardless of the length of the skein and the angle of inclination of the arm 4.

Having described my invention, what I claim is:

1. A guard for guiding a skein of yarn while being unwound on a pair of reels, comprising guiding members adapted to straddle the runs of the skein of yarn between the supporting reels, a cross member connecting said guiding members above the yarn, said guiding members being free or disconnected below the yarn, and means for supporting the guiding means.

2. A guard for guiding a skein of yarn while being unwound on a pair of reels, comprising guiding members adapted to straddle the runs of the skein of yarn between the supporting reels, and means for supporting the guiding means, said support-
⁹⁰ ing means being adjustable in the direction of the length of the skein of yarn and adapt-
⁹⁵ ed to permit the guiding means to be swung out of the path of the skein.

3. A guide for yarn comprising a wire or rod bent to form a plurality of loops connected by a connecting portion whereby the said loops may be disposed on opposite sides of a skein of yarn during the unwinding thereof to guide the yarn.

4. A guide for yarn comprising a wire or rod bent to form a U shaped loop the arms of which are substantially parallel, thence crosswise to form a connecting member at one end of said loop and thence bent to form a second U shaped loop the arms of which are substantially parallel, said U shaped loops being spaced apart in substantially parallel relation.

5. The combination with a yarn winding machine having an arm supporting a pair of spaced reels for holding the skein of yarn, a support adjustable along said arm, and a guide carried by said support and comprising members arranged to straddle the skein of yarn between said reels and to prevent lateral displacement of the yarn.

6. The combination with a yarn winding machine having an arm supporting a pair of spaced reels for holding the skein of yarn, a support adjustable along said arm, a guide adapted to pivot from said support in a plane parallel with the skein of yarn, said guide having members arranged to straddle the skein of yarn between said reels and to prevent lateral displacement of the yarn.

Signed at New York city, county of New York and State of New York, this 17th day of February, 1925.

ISIDOR S. BLEENDES.
